UNITED STATES PATENT OFFICE.

FREDERICK STICKEL, OF CHICAGO, ILLINOIS.

OSCILLATORY WATER-MOTOR.

1,306,863.

Specification of Letters Patent. Patented June 17, 1919.

Application filed December 5, 1916. Serial No. 135,197.

To all whom it may concern:

Be it known that I, FREDERICK STICKEL, citizen of the United States, residing at Chicago, in the county of Cook and State of Illinois, have invented certain new and useful Improvements in Oscillatory Water-Motors; and I do hereby declare the following to be a full, clear, and exact description of the invention, such as will enable others skilled in the art to which it appertains to make and use the same.

This invention relates to improvements in fluid-pressure motors, and more particularly in water motors of the oscillatory type. The invention relates particularly to valve-mechanism for controlling the supply and exhaust of the fluid under pressure actuating the motor to the end that the latter may operate with the greatest degree of efficiency. The main object of the invention is to provide a motor of the type set forth and valve-mechanism therefor which provides for a free-flowing supply of fluid under pressure to the motor, and an equally free discharge of fluid therefrom, and which is simple, efficient and cheap.

The invention consists in the features of construction and combinations of parts hereinafter fully described and claimed.

In the accompanying drawings illustrating the invention:

Figure —1— is a fragmentary view in side elevation of the casing of a motor equipped with valve mechanism embodying my invention, the said valve-mechanism being shown in section, taken on the line 1—1 of Fig. —2—.

Fig. —2— is an end elevation of the motor and valve mechanism therefor.

Fig. —3— is a fragmentary detail section through the motor casing taken on the line 3—3 of Fig. —2—.

The motor comprises the cylindrical casing 1, in the end walls of which the shaft 2 is journaled. Mounted within the said casing 1 is a radially disposed partition member 3 which is provided with a radial slot in which an adjustable fin 4 is mounted; the latter abutting at one end against the shaft 2 and being adjusted to vary its position relatively thereto by means of the set-screw 5 engaging in a threaded opening in the circumferential wall of the housing 1.

Mounted upon one end of the casing 1 is a valve-housing 6 consisting of a tube which

is provided between its ends with five equal annular enlarged portions providing an annular chamber 7 and two pairs of annular chambers 8 and 9 respectively, surrounding the tube 10, which is mounted within said housing 6 and extends the entire length thereof. The said tube 10 is provided with perforations or slots 11 whereby communication between the same and each of the chambers 7 to 9 is established. The portions 60 of the tube 10 intermediate the perforated portions thereof and opposing the choked portions of the casing 6 are smooth and devoid of openings.

The chamber 7 communicates with the 70 supply pipe 12 connected with a suitable source of supply of water or other fluid under pressure, and each of the chambers 8 disposed on opposite sides of the chamber 7 is connected with the ports 13 disposed on opposite sides of and contiguous to the partition member 3 within the motor casing 1. The outer or endmost chambers 9 of the casing 6 communicate with the waste or exhaust pipe 14 at different points between the 80 ends thereof through connecting pipes 9'.

Mounted to reciprocate within the tube 10 is a rod 15 which carries two pistons 17 and 16 which fit snugly within the bore of the tube 10 and are separated from each other a 85 distance equal to the length of two of the chambers 7 and 8, for example. The said rod 15 extends through a stuffing box 18 in one end of the tube 10 and projects into a cylinder 19 mounted upon one end of the 90 casing 6, and which is concentric therewith. Within said cylinder 19 said rod is provided with a piston 20 adapted to be fluid-pressure actuated to reciprocate said rod for disposing said pistons 16 and 17 thereof alternately in the position shown in full lines, and the position shown in dotted lines in Fig. —1—, respectively. The rod 15 is further provided with two stop collars 21 for limiting its reciprocable movement.

Disposed parallel with and contiguous to the cylinder 19 is a cylinder 22 of smaller diameter communicating with the cylinder 19 through two ports 23 and 24 for admitting fluid under pressure to said cylinder 19 105 at opposite sides of the piston 20 therein. Said cylinder 22 is provided with an inlet port 25 for fluid under pressure which is surrounded by an annular casing 26 connected with the supply pipe 27 which is con- 110

connected with the supply pipe 12. A reciprocable rod 28 is axially movable in said cylinder 22 and projects through the stuffing box 29 at one end of the latter. The said rod 5 carries two pistons 30 and 31 which are adapted to become positioned alternately, as shown in full and dotted lines respectively, in Fig. —1—. One end of the cylinder 22 communicates with an exhaust port 32 and 10 the other thereof with an exhaust port 33, both of which are connected with the waste or exhaust pipe 14.

The shaft 2 carries a radially extending piston 34 provided with suitable packings 15 for maintaining a fluid-tight joint between the same and the circumferential and end walls of the housing 1. Externally of said housing the shaft 2 carries a segmental projection 35 which is adapted to engage the 20 collar 36 on the rod 28, and to alternately strike opposite sides of said collar for shifting the pistons 30 and 31 from one position to the other, as aforesaid. In the position shown in Fig. —1— the fluid under pressure 25 is entering the port 13, which is uppermost in Fig. —3—, thereby turning the piston 34 in the direction of the arrow. In the position shown in Fig. —1— the said piston 34 is positioned as indicated in dotted lines, 30 extending midway between the radial side edges of the segment 35. The latter is, therefore, approaching the collar 36 for throwing the pistons 30 and 31 to the positions shown in dotted lines in Fig. —1—.

35 When the pistons 16, 17 and 20 are positioned, as shown in full lines, water or other fluid from the pipe 12 enters the chamber 7, and passes through the tube 10 and perforations or openings 11 into the upper of the 40 chambers 8, and thence into the port 13. At the same time the water or other fluid contained on the opposite side of the piston 34 within the casing 1 is being exhausted through the other of the ports 13, and passes 45 into the lower chamber 8, and through the tube 10 and perforations 11 into the chamber 9, and thus into the exhaust pipe 14.

As the segment 35 strikes the collar 36 it moves the latter into contact with the end of 50 the stuffing box 29 and positions the pistons 30 and 31, as shown in dotted lines in Fig. —1—. When so positioned water or other fluid entering through the pipe 27 passes through the port 23 into the cylinder 19, 55 and moves the piston 20 to the position shown in dotted lines in Fig. —1—, thereby also positioning the pistons 16 and 17, as shown in dotted lines. Water or other fluid from the pipe 12 now enters the chamber 7 60 and passes thence into the lower chamber 8 and lower port 13 into the casing 1, thus reversing the direction of oscillation of the piston 34 and causing the water or other fluid previously admitted to pass out 65 through the port of admission into the up-

per chamber 8, and thence into the chamber 9 and into the exhaust pipe 14 through its connecting pipe 9'.

The inlet and exhaust pipes employed are preferably very large so that the fluid under 70 pressure will be freely admitted with small loss by friction, and similarly freely exhausted. The shifting of the piston-valves or slide valves is very quickly accomplished, it being important that the shifting of the 75 valves occurs with too great rapidity to permit of the motor becoming stalled by a positioning of the several piston valves at points intermediate their limits of movement. The momentum of the piston is relied upon to some extent to effect such rapid shifting of the valves.

My said motor is particularly adapted to actuating the oscillatory washing machines which are very commonly used in households and laundries, particularly the former, and it is well-known that the weight of the clothes and the shifting of the same in its container effects more or less unbalancing and variation in speed of momentum of 80 the rocking container therefor. This will aid in the satisfactory operation of the motor, as will be obvious.

While I have shown my invention in its preferred embodiment it will be understood, 95 of course, that such construction may be changed and varied as mechanical skill and adaptation may dictate without departing from the invention as defined in the appended claim.

I claim as my invention:

In an oscillatory fluid pressure motor, a cylindrical chamber, a rock-shaft journaled in bearings disposed axially thereof, a radially disposed partition member extending 105 from the shaft to the circumferential wall, ports on opposite sides of said partition member each constituting alternately an inlet and exhaust port, a radially disposed piston mounted on said shaft, a valve-casing common to both said ports, said casing having a central chamber connected to a fluid pressure supply pipe, the casing having two chambers at each side of the central chamber, each of the chambers nearest adjacent to the central chamber communicating with one of said ports, an exhaust pipe, each of the farther chambers communicating with the exhaust pipe, a tubular lining 110 in said casing having openings in its wall connecting the interior thereof with the several chambers, a piston slide valve in said tubular lining for alternately connecting one of said ports with the central chamber while connecting the other port with its adjacent outer chamber, a cylinder beyond one end of said valve casing, a piston rod for said slide valve, a piston thereon reciprocable in said cylinder, a slide valve housing 115 parallel with said cylinder and having two 120

125

130

ports communicating with said cylinder on opposite sides of said piston, a slide valve in said housing, connection between the same and said source of fluid under pressure, a 5 valve rod for said slide valve, and valve actuating means including a member rigid with the piston, and valve-rod shifting means disposed in the path of and adapted to be engaged alternately by the member as 10 same approaches the respective limits of its

movement whereby to shift the valve to reverse the flow as the piston approaches the respective limits of its movement.

In testimony whereof I have signed my name in presence of two subscribing wit- 15 nesses.

FREDERICK STICKEL.
